(57) **CLAIM**

The ornamental design for an electronic console, as shown and described.

DESCRIPTION

FIG. 1 is an isometric view of an electronic console showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged view of the encircled portion labeled as **8** in FIG. 1;

FIG. 9 is an enlarged view of the encircled portion labeled as **9** in FIG. 3;

FIG. 10 is an enlarged view of the encircled portion labeled as **10** in FIG. 6; and,

FIG. 11 is a cross-sectional view taken through line **11-11** of FIG. 6, showing the concave upper region of the electronic console.

In the drawings the even length broken lines depict features that form no part of the claimed design. The uneven length broken lines shown in FIGS. 1, 3, 6, and 8-11 show boundaries of the enlarged portions and form no part of the claimed design.
